[57] CLAIM

The ornamental design for a cookware cover handle, as shown and described.

DESCRIPTION

FIG. 1 is a perspective view of a cookware cover handle in accordance with my new design;

FIG. 2 is a front elevational view thereof, the rear elevational view being a mirror image of the front view shown;

FIG. 3 is a top plan view thereof;

FIG. 4 is a bottom view thereof;

FIG. 5 is an end elevational view thereof as viewed from the left of the front view; and,

FIG. 6 is an end elevational view thereof as viewed from the right of the front view.

The broken lines showing further details of the cookware handle are for illustrative purposes only and form no part of the claimed design.
